UNITED STATES PATENT OFFICE.

EDWARD BEACH HOWELL, OF BUTTE, MONTANA.

BLOCK MOLD.

1,421,006.

Specification of Letters Patent. Patented June 27, 1922.

Application filed March 2, 1921. Serial No. 449,052.

To all whom it may concern:

Be it known that I, EDWARD BEACH HOWELL, a citizen of the United States, and a resident of Butte, in the county of Silver Bow and State of Montana, have invented certain new and useful Improvements in Block Molds, of which the following is a specification.

My invention relates to molds for forming blocks of plastic material and more particularly to flanged blocks used in building construction.

The purpose of my invention is the provision of a mold which forms, without recourse to substitution or any changing of parts, blocks of any desired length within the range of the mold so that when making the blocks necessary to the formation of a building wall, the one and only mold can be employed throughout.

It is also a purpose of my invention to provide a plurality of block molds which coact one with the other to simultaneously form a plurality of blocks of the same or different lengths whereby, the making of a number of blocks in the form of building walls, is facilitated.

I will describe one form of mold embodying my invention and will then point out the novel features thereof in claims.

In the accompanying drawings:

Figure 1 is a plan view partly broken away showing three molds of like construction embodying my invention.

Figure 2 is a fragmentary transverse sectional view taken on the line 2-2 of Figure 1.

Figures 3 and 4 are transverse sectional views taken on the lines 3-3 and 4-4, respectively, of Figure 1.

Figure 5 is a longitudinal sectional view taken on the line 5-5 of Figure 1.

Figure 6 is a fragmentary perspective view of the forms employed in one of the molding units shown in Figure 1.

Figure 7 is a detail perspective view of the end block employed in one of the molding units shown in Figure 1.

Similar reference characters refer to similar parts in each of the several views.

Referring specifically to the drawings and particularly to Figure 1, my invention in its present embodiment is shown as consisting of a plurality of molding units, and although I have shown and will describe only three of these molding units, it is to

be understood that any number of units can be employed with the present construction by merely multiplying the parts comprised in each unit. The several molding units are 60 designated at M, M', and M'', and are supported on a common base consisting of a plurality of regularly spaced beams 15 arranged parallel to each other and to a mid-rail or beam 16. The mid-rail 16 serves the 65 double function of providing a dividing partition at the confronting ends of any two adjacent molds, and is sufficiently wide to allow of the passage of wheel barrows there-over or for the accommodation of a track 70 over which suitable cars can be moved to any particular mold for discharging the concrete within the molds.

Any two adjacent molding units are comprised of three partitions 17 which are movable on the beams 15 and which in their applied position are arranged at right angles to the mid-rail 16 and in parallel spaced relation to each other. Each partition 17 is in the form of an I-beam, as 80 clearly shown in Figures 3 and 4, the flanges at the upper and lower edges of the beam coacting to provide grooves at the opposite sides thereof. Slidably fitted between any two partitions 17 is a filler block F which is 85 preferably formed of sheet metal bent to provide a raised intermediate portion 18, divergent side portions 19, and laterally extending flanges 20 formed on the free edges of the side portions. End portions 21 are 90 also provided at the opposite ends of the filler block, these end portions being provided at their free edges with laterally extending flanges 22, as clearly shown in Figure 6.

In the applied position of any one of the filler blocks F, the side flanges 20 are supported on the lower flanges of any two adjacent partitions 17 in the manner clearly shown in Figures 2 and 4. In this position, 100 the intermediate portion 18 is disposed slightly below the level of the upper edges of the partitions so as to provide a space therebetween for the reception of concrete. This body of concrete is adapted to form the 105 panel portion of a block formed by the molding units. As shown in Figure 2, the divergent side portions 19 are spaced apart from the confronting sides of the partition 17 and within these spaces concrete is adapted to be deposited, as shown, to provide the side flanges of the concrete block. The end

flanges of the concrete block are formed by the coaction of the end portions 21, flanges 22 and stationary end blocks 23 arranged contiguous to the mid-rail 16 and extending 5 transversely between the partitions. At the other end of the filler block, the end flange may or may not be formed, but when such flange is desired it is formed by an end block 24 which as shown in Figure 7 is recessed 10 at its upper edge to provide tongues at the opposite ends thereof which are adapted to slidably fit within the grooves of the partitions. In the applied position of the end block 24 as shown in the molding unit M', 15 it coacts with the adjacent end of the filler block to form the end flange, as will be understood.

From the foregoing arrangement, it will be clear that the several filler blocks F together with the end blocks 23 and 24 will maintain the partitions 17 in definite spaced relation upon the base beams 15. However, in order to maintain the partitions 17 in firm contact with the filler blocks and end blocks, 25 I provide stationary clamping blocks 25 and movable clamping blocks 26 arranged upon the base beams 15 so as to clampingly embrace the partitions and thus secure them against lateral movement. As shown in Figure 1, the stationary clamping blocks 25 are 30 fixedly secured to the beams 15 by fastening members 27 so as to form an abutment for the outermost partition to the right. The movable blocks 26 are arranged upon the beams 15 to engage the outermost partition to the left and are adjustable to force such partition and the intermediate partitions in the direction of the outermost partition to the right. In the present instance this adjusting means for the blocks 26 comprises 35 castings 28 slidably mounted upon the beams 15 and carrying screw threaded spindles 29 which are secured to the movable blocks and threadedly fitted within the castings so that 40 when rotated in the proper direction a forward feeding of the blocks is effected to move the partitions in clamping relation with respect to each other. The castings 28 are also adjustable upon the beams 15, and for 45 this purpose the beams are perforated at regular spaced intervals as indicated at 30 in Figure 2, and in any one of these perforations pins 31 can be inserted. The opposite ends of the pins 31 are embraced by 50 the ends of links 32 pivotally supported upon the casings, and with the pins and links associated with each other in the manner shown, it will be clear that the castings can be locked against longitudinal movement on 55 the beams and to thereby hold the movable clamping blocks 26 in definite relation with respect to the partitions.

In the operation of any one molding unit, the filler block F and the end blocks 23 and 60 24 are arranged in proper positions between

any two adjacent partitions so that when the movable clamping blocks are properly adjusted the two partitions will be held in firm engagement with the blocks. Concrete or other like material is now deposited upon the filler block and between the spaces or channels formed between the confronting side and end portions of the filler block and the partitions and end blocks. It is to be particularly noted that the concrete can be 70 readily spread over the surface of the molding unit so as to completely fill the mold because there are no protruding obstructions extending above the surface of the mold to prevent the sweeping of a board or other 80 suitable tool across the surface of the mold which will insure the disposition of concrete within all parts of the mold to properly form the block. In this manner a block is 85 molded having a panel portion of substantially rectangular outline with slightly divergent side and end flanges which are co-extensive in length with the sides and ends of the panel portion. When the concrete is properly set, it will be clear that the molding 90 unit can be readily disassembled by moving the clamping blocks 26 to releasing position so as to permit the spreading of the partitions 17 and the consequent removal of the 95 filler block.

To demonstrate the range of the molding units as constructed in accordance with my invention, the molding unit M is shown as provided with an auxiliary filler block F' which is constructed in the manner shown in 100 Figure 6 so that it can be extensively associated with one end of the filler block F and applied in the manner shown in Figure 1. By this arrangement the length of the molding block can be readily varied to meet any 105 particular requirement in the formation of a building wall. Within the building unit M', a window filler member W is arranged so as to divide the block which would be ordinarily molded, into two separate and distinct sections. As illustrated in Figure 2, the member W comprises a panel portion 33 of rectangular outline which overlies the panel portion of the filler block F, and flange portions 34 adapted to be disposed within the 110 spaces between the partitions and side portions of the filler block. The panel portion 33 is flush with the upper edges of the partitions 17 so that when the concrete is deposited within the molding unit, and properly spread, it will be deposited within the mold at the opposite ends of the member W so as to form the two block sections. As 115 will be understood, these two block sections are necessary in the formation of the window openings in a building wall.

In the molding unit M', a follower R is so adjustably mounted between the partitions 17 so as to be movable longitudinally of the molding unit. The follower R comprises a 120

horizontal portion 35 on the opposite ends of which are formed depending flanges 36. The portion 35 is adapted to overlie the panel portion of the filler block F, with the 5 flanges 36 disposed between the sides of the filler block and the partitions. This arrangement permits of the formation of a concrete block of any desired length within the range of the mold having at one end only a 10 transverse flange, it being understood that the concrete is deposited on the filler block between the end block 23 and the follower R.

What I claim is:

1. A block mold comprising, a base, partitions upstanding from the base, filler blocks on the base, said partitions and filler blocks being so shaped and associated with each other and with said base as to provide side channels and an end channel communicating with the side channels, the upper edges of all of the channels being open, and the follower movable in the side channels and over the filler blocks for the purpose described.
- 25 2. A block mold comprising, a base, partitions upstanding from the base, means on the base and between the partitions and coacting with the latter to provide open sided channels and a space between the 30 channels into which a material is adapted to be deposited, and a follower movable within certain of the channels and through said space and adapted to define one end of the mold whereby the length of blocks molded 35 within the form may be varied.

3. A block mold comprising, partitions supported for bodily movement laterally, and filler blocks arranged between the partitions so as to coact with the partitions in forming 40 a block having flanges when a plastic material is introduced between the partitions.

4. A block mold comprising, a pair of spaced partitions, one of which is movable bodily relatively to the other filler blocks 45 arranged between the partitions so as to coact with the partitions in forming a block having flanges when a plastic material is introduced between the partitions, and adjustable means for securing the partitions in 50 clamping relation with respect to the filler blocks.

5. A block mold comprising, a base, grooved partitions slidably mounted on the base, filler blocks arranged between adjacent 55 partitions and adapted to coact with the partitions for defining substantially U-shaped channels, and means mounted on the base for moving and securing the partitions in clamping relation with respect to the 60 filler blocks.

6. A block mold comprising, a base, grooved partitions slidably on the base, filler blocks between the partitions and each comprising a panel portion disposed below the 65 upper edges of the partitions, and flanges

between the panel portion and the partitions and at the opposite ends of the panel portion, end blocks fitting between the partitions and spaced from the panel portion by the end flanges, and means carried by the 70 base for securing the partitions in clamping relation with respect to all of said blocks.

7. A block mold comprising, a base, partitions movable on the base, a filler block between the partitions, end blocks between the 75 partitions, one of said end blocks being movable toward and away from the filler block, and a filler member including a panel portion overlying the filler block, and flanged portions interposed between the 80 filler block and the partitions.

8. A block mold comprising, a base, partitions slidable on the base, a filler block between the partitions comprising a panel portion disposed below the upper edges of 85 the partitions, side flanges for maintaining the panel portions spaced from the sides of the partitions, and end flanges, a stationary block between the partitions at one end thereof and spaced from the panel portion 90 by one of the end flanges, and a follower slidably fitted between the partitions and including a horizontal portion overlying the panel portions of the filler block, and depending flanges movable between the sides 95 of the panel portion and the partition.

9. A block mold comprising, a plurality of base beams, a mid-rail secured to one of the beams, stationary clamping blocks secured to the beams, partitions loosely 100 mounted on the beams and arranged at right angles to the mid-rail, filler blocks arranged between the partitions and adapted to coact with the latter to provide a substantially U-shaped channel open at its 105 upper side, and movable clamping blocks adjustable on the beams to engage the partition and move the latter in clamping relation with respect to the filler blocks and in abutting relation to the stationary clamping 110 blocks.

10. A block mold comprising a base, a pair of normally parallel I-beams superimposed upon said base, one of said I-beams being movable laterally on the base, filler 115 blocks for spacing said I-beams and for co-operating with said I-beams to define a channel of U-shaped cross section, end blocks co-operating with the filler blocks and with the I-beams to define channels connecting the 120 sides of said first named channel at the ends thereof, all of said channels being open along their upper edges to permit the filling thereof with a plastic substance, and means for moving the movable I-beam bodily relatively to the other I-beam and for securing the movable I-beam in position to occasion the clamping of the said blocks between said I-beam.

11. A block mold comprising a base, a pair 130

of normally parallel I-beams superimposed upon said base, one of said I-beams being movable laterally on the base, filler blocks for spacing said I-beams and for cooperating with said I-beams to define a channel adapted to receive a plastic material, a clamping block slidable on the base and movable against the side of the movable I-

beam remote from the other I-beam, a casting adjustably and detachably secured to the base adjacent to the clamping block and means carried by the clamping block and threadedly engaging the casting for holding the movable I-beam in desired relation to the other I-beam.

EDWARD BEACH HOWELL.
